APPARATUS FOR FINISHING SURFACES

Walter I. Knapp, Detroit, Mich., assignor to
 Frederic B. Stevens, Inc., Detroit, Mich., a corporation of Michigan

Application March 18, 1946, Serial No. 655,306

7 Claims. (Cl. 51—57)

1

This invention relates to apparatus for finishing utensils or vessels such as pots, pans and skillets. More particularly, this invention refers to an automatic machine for finishing the surfaces of cast, drawn or spun utensils such as aluminum, copper or iron pans or skillets.

In the manufacturing of utensils a final step is that of finishing the surface. This finish is usually obtained by spinning the utensil in a chuck and manually abrading the surface with a piece of emery cloth or similar flexible cutting medium. In order to obtain the uniform and neat appearing results required, considerable skill must be employed in manipulating the abrasive member. In addition, the manual processing of the utensils is slow and the results at best are variable.

The object of the present invention is to provide a machine for mechanically finishing the insides of utensils and to obtain a result equal or better than is possible by manual means.

Another object is to provide such a machine which will be fully automatic.

Still another object is to provide an automatic machine for applying the final finish to the insides of utensils which includes a turret for holding the workpieces.

Still another object is to provide a machine according to the foregoing objects which is adjustable for different types and sizes of utensils.

Another object is to provide an apparatus for finishing the insides of utensils by abrading such that an improved product results and such that the rate of production is substantially increased.

It is also an object to provide, in connection with a machine according to the foregoing objects, safety limits by means of which the machine is halted suddenly in case of breakage, misadjustment or improper operation.

These and other objects and advantages will become more apparent upon reference to the following description and the accompanying drawings in which:

Figure 1 is a plan view of a machine constructed according to this invention;

Figure 2 is a side view of the machine looking in the direction of the arrow 2 on Figure 1;

Figure 3 is a section taken substantially along the line 3—3 of Figure 2;

Figure 4 is a view taken substantially along the line 4—4 of Figure 3 showing one of the adjustments of the machine;

Figure 5 is an enlarged view of the lower end of the abrading arm in operative position;

2

Figure 6 is a section on the line 6—6 of Figure 5 showing one of the safety limits;

Figure 7 is a view looking substantially in the direction of the arrows 7—7 on Figure 5;

Figure 8 is a section taken on the line 8—8 of Figure 5 showing the contour of the shoe at the end of the abrading arm;

Figure 9 is a section taken substantially along the line 9—9 of Figure 2 and shows the connections to the vacuum chuck in the turret;

Figures 10, 11 and 12 are fragmentary views showing the abrading arm and the actuating mechanism therefor in different operative positions during a cycle; and

Figure 13 is a wiring diagram for controlling the actuation of the abrading arm and the turret indexing motors.

General arrangement

A machine constructed according to, and adapted for practicing the methods of, this invention comprises means such as a chuck for supporting and rotating a utensil such as a pan or skillet. Preferably, there are a plurality of these chucks mounted in a turret so that one after the other is indexed into working position.

For finishing the inside surface of the pan or skillet there is provided an abrading arm having an end shaped to conform to the contours of the pan and comprising an abrasive, preferably in the form of a flexible tape such as emery cloth and of a texture of from number 80 to 100. When tape is used as the abrading medium, a mechanism is provided for shifting the tape a predetermined amount for each cycle so that a fresh abrading surface is presented to each utensil.

For actuating the abrading arm there is provided cam and linkage mechanisms which are driven in rotation by a suitable motor means. The cams and linkage drive the abrading arm so that the tip thereof follows the surface of the utensil being finished and the cam may be so shaped and the links so proportioned that the contour of any utensil may be followed with great exactness.

A uniform pressure on the utensil is obtained by suitable yielding means which continuously urge the abrading tip of the abrading arm into engagement with the surface of the utensil.

Suitable means such as limit switches are located on the abrading arm so that improper operation of the machine, breakage of the abrasive tape, or maladjustment of the machine, will immediately bring the machine to a halt, and main-

tain it in a halted position until the trouble has been cleared.

In addition to the cam and linkage which may be replaced to vary the path through which the abrading tip passes, the machine includes means for raising and lowering the abrading mechanism as a unit, for moving it toward or away from the working station as a unit, or for bodily tilting the abrading mechanism.

Structural arrangement

Referring to the drawings and particularly to Figures 1 through 5, a machine according to this invention comprises a bed 10 which adjustably supports a foot member 12 having, in turn, adjustably connected therewith the column 14.

The column 14 carries a table 16 to which is pivoted, as at 18, a plate 20. In Figures 3 and 4 it will be noted that the table 16 is vertically adjustable on the column 14 by the rack 22 on the latter and the gear 24 carried by the former. The gear 24 is connected through the shaft 26, the self-locking worm mechanism 30 and the shaft 28 with a manual adjusting means at 32 which is operable to raise and lower the table 16 on the column 14. The plate 20 is abutted by a screw 34 which passes through the table 16 and which is selectively operable to tilt the plate about its pivot 18 to any desired degree of angularity.

The plate 20 has secured thereto the upstanding plate 36 upon which is carried the abrading mechanism generally indicated at 38. The abrading mechanism consists of an arm 40 which is slidably through a bearing block 42, which has at its lower end the abrading tip generally indicated at 44 and which is pivoted at its upper end at 46 to an arm 48. The arm 48 is pivoted between its ends as at 50 to the plate 36 and has a pivot 52 at its other end.

Pivoted to the arm 48 at 52 is another arm or link 54 which has a slot 56 therein which slides over a shaft 58 extending through the plate 36. Optionally the shaft 58 may have a roller or other suitable journaling means whereby the reciprocation of the link 54 relative thereto is facilitated.

The shaft 58 has connected therewith a cam 60 which has a cam track 62 formed into the face thereof. The cam track 62 receives a roller or follower 64 which is secured to the arm 54. As the cam rotates the arm 54 is reciprocated and rocks the arm 48 and is guided in its reciprocation by the slot 56 which passes over the shaft 58.

Connected with the end of the shaft 58 and overlying the arm or link 54 is a link 66 which has its end pivotally connected as at 68 with a lug outstanding from the bearing block 42. The several links may comprise a plurality of points for receiving the several pivots and the cam 60 may be replaced by another with a modified cam track for the purpose of varying the path through which the arm 40 passes. The particular arrangement shown in the drawings is for the purpose of finishing the inside of a pan having a flat bottom and vertical side walls.

For driving the cam 60 in rotation, the shaft 58 is connected through the reduction gearing 59 with the output shaft 61 of a speed reducing transmission 63. The input shaft of the transmission 63 is connected to be driven by the electric motor 65. The motor and speed reducer are mounted on the plate 20 in any suitable manner.

The utensil to be finished is indicated at 70 in Figures 1, 2, and 5 and will be seen to be supported in a chuck 72 which has a plurality of passages 74 and ports 76 therein. The passages 75

74 lead to a central passage 78 which passes vertically downwardly through the spindle 80 of the chuck to a plurality of substantially radial passageways which terminate in a circumferential groove about the said spindle. This groove is indicated at 82 and is in communication with a passage 84 in the turret plate 86 which supports the several chucks.

The turret plate 86 is carried on a central column 88 and is journaled in the upstanding portion 90 of the machine bed 10. For clamping the utensil in the chuck at the working station, there is provided a passage 92 in the portion 90 which is connected at one end with a vacuum conduit 94 and, at the other end, with a recess 96 which registers with the passage 84 when the turret brings the chuck into working position. The turret may be indexed by any suitable means but it is preferred to employ the Geneva mechanism 20 consisting of the slotted plate 98 which is engaged by the rotary plate 100 having the indexing pin 102. The plate 100 may be driven by any suitable means but, for the purposes of illustration, the motive power is shown in the drawings as comprising an electric motor 104.

The slotted plate 98 and the plate 100 carrying the pin 102 operate in the manner of a regular Geneva mechanism, the pin 102 engaging one of the slots of the plate 98 as the plate 100 rotates and indexing the plate 98 through 90 degrees to bring another workpiece into the work station. The raised part in the center of the plate 100 acts as a key to retain the plate 98 in its indexed position. It will be understood that the plate 100 could be operated continuously or intermittently, as desired, depending on the rapidity with which it is wished to index the turret 86.

For rotating the chuck 72 which is in working position, the spindle 80 thereof is coupled with the drive shaft of a motor 104 which is carried on a plate 106 attached to the turret plate 86. The motor 104 is adapted for energization when the chuck to which it is attached is moved into working position by means of the brush mechanism and slip ring indicated at 108.

Returning to the abrading arm, and particularly to the abrading tip 44, this portion of the mechanism is more clearly seen in Figure 5. The arm 40 comprises a rectangular or cylindrical tube having connected therewith a plate 110. Adjustably mounted within the plate 110 is a rod 112 that extends downwardly and has a head 114 thereon. Slidably mounted in the end of the arm 40 is a framework 116 which carries the abrading tip mechanism which has been indicated generally at 44. The said mechanism is urged downwardly by a spring 118 which bears between a plate 120 secured to the framework 116 and a plate 122 which is adjustably supported in the arm 40 as by the screws and wing nuts 124 which extend through the slots 126 in the arm 40.

The framework 116 extends downwardly from the arm 40 and carries a channel portion 128 which has journaled in the lowermost end thereof a roller 130 of some suitably resilient material such as felt. The roller 130 is preferably curved to have a somewhat greater curvature than the utensil being finished as is indicated in Figure 8.

Passing around the roller 130 is a flexible tape 132 which is coated with emery or a similar abrasive and preferably of about the texture of No. 80 to No. 100 emery. The tape 132 is paid off from a reel 134 carried between a pair of arms which

extend laterally from the framework 116. A tension spring 136 connected between the reel 134 and the supporting bracket therefor continuously urges the said reel in its taking up direction with a substantially constant torque, whereby a substantially predetermined tension is maintained on the tape 132. After the tape passes around the roller 130, it is attached to a take-up reel 138 that is also carried in a pair of arms extending from the framework 116. The reel 138 has connected therewith a ratchet wheel 140 which is engaged by a spring pressed pawl 142. A second pawl 144 is urged away from the said wheel by a spring 146. The tape is guided between the reels by the channel guards 133 and 135 and passes over a roller 137 immediately before passing to the takeup reel.

As will become apparent hereinafter when the arm 40 is moved upwardly and out of the utensil 70, the upper end of the pawl 144 strokes the arm 148 carried on the bearing block 42 and actuates the said pawl to index the reel 138 to take up the predetermined amount of the tape 132. This automatically provides a fresh abrasive surface to be presented to the next utensil to be finished.

The spring 118 urges the abrading tip against the bottom of the utensil with a predetermined thrust and, when the arm 40 is moved to present the abrading tip to the side of the utensil, the hinge 150 and spring 152 provide tensioning means for urging the abrading tip laterally against the side of the utensil with a substantially equal thrust.

In connection with Figure 2, Figures 10, 11 and 12, illustrate the cam, links and abrading tip in several of its operative positions during a work cycle. In Figure 2, the abrading tip is resting in the center of the bottom of the utensil. In Figure 10, the cam 60 has rotated about 60° and the abrading tip has reached the corner of the utensil. It will be noted that the roller 130 has a radius not greater, and preferably smaller, than the radius of the fillet in the corner of the utensil. In Figure 11, the cam has rotated until the abrading tip has reached the upper edge of the utensil side wall, and in Figure 12, the cam is turned to bring the abrading tip substantially vertically above the starting position indicated in Figure 2.

For actuating the cam driving motor 65 and the turret indexing motor 154, there is provided the electrical circuit illustrated in Figure 13. In this figure, the power lines are indicated at L1 and L2 and therebetween are connected the several circuit components.

Connected serially between the line L1 and the remainder of the electric circuit are the switches indicated at 156, 158 and 160. The switch at 156 is an emergency stop switch which is normally closed and which is opened to de-energize the electrical circuit if the machine is improperly adjusted or jams from faulty metal. The switch 156 is indicated in Figure 6 wherein it will be seen to comprise mating contacts carried on the framework 116. The framework is divided between the contacts and there is a hinge 162 which permits the contacts to open when the lower portion of the framework 116 is pivoted relative to the upper portion. The lower portion of the framework is yieldably retained in position by the spring and detent mechanism indicated at 164.

The switch 158 is a sensitive limit switch and is carried in the U-shaped member 128. The

switch 158 is normally held closed by its actuating roller 166 which is engaged by the tape 132. When the tape breaks, runs off the payoff reel, or loses tension for any other reason, the switch 158 opens to halt the machine.

The switch 160 is a manually operated on and off switch and is preferably carried on the table 16 or in any other position convenient to the machine operator.

The side of the switch 158 opposite the line L1 is connected with a line 168 which, in turn, is connected through the limit switch LS1 and the contactor coil B with the line L2. The limit switch LS1 is carried on the machine bed and is actuated into closed position by the cams 170 carried on the turret plate 86. The contactor coil B has the normally open blade B1 which is in series with the cam motor 65 between the lines 168 and L2. The blade B1 is bypassed by the normally closed blade A1 of the contactor A which is in series between the lines L2 and 168 with the normally open limit switch LS3.

The switch LS3 is preferably carried on the bearing block 42 and is adapted for being actuated into closed position by an adjustable abutment 172 connected with the arm 40. When the arm 40 is moved to its Figure 12 position, the switch LS3 is actuated to its closed position to energize the contactor coil A and to open the blade A1 thereof.

Connected between the lines 168 and L2 is a contactor coil C in series with a selector switch 174, and a normally open limit switch LS2. The limit switch LS2 is bypassed by the push button station 176 and a holding circuit consisting of the normally open blade C2 and the normally closed limit switch LS4. The limit switch LS4 is carried on the machine bed and is actuated into opened position temporarily by the cams 170 as the turret rotates. The limit switch LS2 is preferably supported on the bearing block 42 and is temporarily actuated into closed position as the arm 40 moves upwardly and toward its Figure 12 position. The selector switch 174 may be closed as indicated for full automatic operation of the machine and opened for semi-automatic to initiate a new cycle. When the switch 174 is opened, the push button 176 must be closed to inaugurate each new cycle.

50 The contactor coil C has the normally open blade C1 in series with the turret indexing motor 154 and, when the coil C is energized, the index motor operates to rotate the turret. The blade C1 is bypassed by the normally closed blade B2 of the coil B.

In order quickly to halt the operation of the machine in the event that either of the emergency limit switches or the hand switch 160 is opened, the motors may be provided with a magnetic brake construction, one of which is shown in association with the cam driving motor 65. The brake construction consists of a drum 178 carried on the motor shaft and a pair of shoes 180 surrounding the drum and urged away from the said drum by a spring 182. A solenoid and armature indicated at 184 is adapted, when energized, to actuate the brake mechanism and thereby suddenly to halt the rotation of the drive motor. For actuating the solenoid 184, there is provided in a series therewith the normally closed blade D1 of the contactor coil D. The solenoid 184 and the blade D1 are connected between the lines L1 and L2 while the coil D is connected between the lines L2 and 168. When any of the switches 156, 158 or 160 are opened, the coil D

is deenergized, the blade D1 thereof closes and the solenoid 184 is energized immediately to actuate the brake or brakes for halting the cam motor or the cam motor and the turret motor together.

Operation

In operation, a pan-shaped workpiece, such as a kitchen utensil, is placed in the turret and indexed into position under the abrading station. When the turret reaches working position, the switch LS1 is actuated to energize the coil B thereby to close the blades B1 thereof and to open the blades B2 thereof. Opening of the blades B2 deenergizes the turret motor 154 and closing of the blades B1 energizes the cam motor 65.

Energization of the cam motor 65 drives the abrading arm through its path to finish the interior of the utensil 70, the said utensil being driven in rotation by its supporting chuck 72. When the abrading arm has finished its working stroke and is approaching its Figure 12 position, it actuates the limit switch LS2 into closed position. Closing of LS2, if switch 174 is closed, energizes the coil C which is held by the holding circuit including the blade C2 and the switch LS4.

Energization of C closes the blade C1 and energizes the turret indexing motor. The turret therefore commences its indexing movement. The abrading arm 40 continues its upward movement until it passes the limit switch LS2 and strikes the limit switch LS3. Closure of the limit switch LS3 energizes the contactor coil A to open the blade A2 thereof thereby to deenergize the cam motor 65. At this time, the turret has indexed to the position where the cam 170 permits the limit switch LS1 to open so that the coil B is deenergized and the blade B1 thereof is opened and blade B2 thereof is closed.

The cam motor thus remains deenergized. As the indexing movement of the turret progresses, one of the cams 170 opens the limit switch LS4 and deenergizes the coil C. Deenergization of C opens the blade C1 thereof but the indexing motor 154 continues to operate because of the blade B2 which is closed.

When the turret has indexed to the point where one of the cams 170 closes the limit switch LS1, the coil B is energized and a new cycle is commenced.

If the switch 174 were opened, the abrading arm would go through one cycle and halt in its upper position and a new cycle would be instituted by closing the push button 176.

If, at any time, the emergency switch 156 or the limit switch 158 or the hand switch 160 is opened, both of the drive motors are immediately deenergized while the brake or brakes associated with one or both thereof are energized to bring the entire mechanism to a sudden stop.

It will be understood while only one form of utensil has been illustrated in the accompanying drawings, the abrading mechanism is capable of adjustment to perform a finishing operation on substantially any size or shape pan, skillet or the like.

In any case, the finish on the utensil or vessel is uniform, precise, neat appearing and quickly accomplished so that there is a material saving in labor, and an improvement in the quality and appearance of the finished product.

It will be understood that this invention is susceptible to modification in order to adapt it to different usages and conditions and, accordingly, it is desired to comprehend such modifica-

tions within this invention as may fall within the scope of the appended claims.

I claim:

1. In an apparatus for finishing abrading one of the inner and outer surfaces of a pan-shaped workpiece, means for supporting and rotating said workpiece, a movable arm, an abrading member yieldably carried on the end of said arm to be moved thereby over said surface from the center of rotation of said workpiece outwardly, a joint in said arm, switch means responsive to a predetermined thrust on said abrading member transverse to its direction of movement across said surface for breaking said joint thereby permitting said abrading member to deflect away from the surface being finished, motor means energizable to actuate said arm, and switch means responsive to the deflection of said abrading member for de-energizing said motor means and for halting movement of said arm.

2. In an apparatus for finishing one of the inner and outer surfaces of rotating pan-shaped workpieces, means for supporting and rotating said workpiece, a movable arm; electric motor means energizable to actuate said arm, a finishing member yieldably carried on the end of said arm, a joint in said arm adapted for being broken in response to a predetermined thrust on said finishing member lateral to its direction of movement, electrical contacts in circuit with said motor means, and means carried on said arm and adapted to be actuated by the breaking of said joint to actuate said contacts to de-energize said motor means.

3. In combination, in a machine for abrading a surface on a workpiece, means for supporting and rotating said workpiece on an axis passing through the center of said surface, an arm, abrading means carried on the said arm comprising a supply of abrasive tape extending over the end of the arm, power means to actuate said arm to carry said abrading means in a closed path a part of which is along and in engagement with the said surface and the other part of which is idle travel, means operable during the idle travel of said arm to feed said tape, and switch means responsive to the breakage of said tape to halt said power means.

4. In combination, in a machine for abrading a surface on a workpiece, means for supporting and rotating said workpiece on the axis of symmetry of the surface to be finished, an arm, abrading means carried on the said arm comprising a supply of abrasive tape extending over the end of the arm, takeup means to tension said tape, power means energizable to actuate said arm to carry said abrading means in a closed path a portion of which is along and in engagement with surface being finished and the remainder of which is idle return travel along a line spaced from the said surface, means to feed a predetermined amount of said tape during the idle travel of said arm, and switch means operable automatically to de-energize said power means when said tape loses tension.

5. In a machine for finish abrading a surface of a workpiece, means for supporting and rotating a workpiece having a bottom and peripheral wall about the axis of symmetry of the said surface, an arm, a roller carried on the end of said arm adjacent the surface to be finished, and abrasive coated ribbon passing over said roller for abrading the said surface, a pay-off reel and a takeup reel for said ribbon carried on said arm and one thereof being spring urged to tension said ribbon

and the other thereof being intermittently actuated to feed a predetermined amount of ribbon over said roller, power means energizable to actuate said arm to carry said roller over the surface being finished from the initial contact at the said axis of the workpiece outwardly to the peripheral wall and along the peripheral wall, and switch means responsive to loss of tension in said ribbon for automatically de-energizing said power means thus to bring said machine to a halt.

6. In a machine for finish abrading the inner surface of a rotating pan-shaped workpiece, means to support and rotate said workpiece, a movable member adapted to have its end positioned against and moved across said surface, an abrading means carried by said member to be moved across said surface thereby, said abrading means comprising a resilient roller of a curvature in any plane greater than the curvature of said inner surface in the same plane, a flexible abrading ribbon passing over said roller, and ratchet wheel means operable automatically to feed said ribbon a predetermined amount after each movement across said surface to present a new abrading surface to each workpiece.

7. In a machine for finish abrading the inner surface of a rotating pan-shaped workpiece, a turret, a plurality of rotatable work supporting chucks on said turret, means for indexing said turret to bring said chucks consecutively into a work station, means operable to clamp workpieces in said chucks when in said work station and for rotating said chucks, abrading mechanism including a movable arm adjacent said work station adapted to contact the inner surface of the workpiece at the axis of rotation, an abrading end part on said arm, power means to actuate said arm to move said end part in a closed path

of which a part is the same shape as said inner surface from the initial contact point at the axis of rotation of the workpiece outwardly, a column adjustably supported adjacent said turret, and means adjustably supporting said abrading mechanism on said column.
